SUCTION CLEANER

Harry B. White, Canton, Ohio, assignor to The
Hoover Company, a corporation of OhioApplication January 24, 1929, Serial No. 334,617
Renewed January 23, 1933

16 Claims. (Cl. 15—8)

This invention relates to suction cleaners and more particularly to suction cleaner nozzles.

Broadly the invention is characterized by the provision of a floating sub-nozzle within the main nozzle of the cleaner whose height above the surface being cleaned is automatically adjusted by means which are pressure responsive.

The primary object of the invention is the provision of an improved and superior form of suction cleaner nozzle.

10 A further object is to provide a suction cleaner nozzle so constructed that maximum cleaning efficiency is insured through the constant maintaining of the nozzle lips in operative relation to the surface to be cleaned.

15 A still further object is the provision of a new and novel nozzle structure which is characterized by ruggedness and simplicity coupled with sensitivity and reliability in its automatic height adjusting features.

20 Other objects and advantages will become apparent upon reading the specification in connection with the accompanying drawing.

The invention is fully illustrated in a preferred 25 embodiment in the accompanying drawing in which like reference characters refer to like parts in the various views and in which:

Figure 1 is a side view of a suction cleaner nozzle showing the nozzle mechanism.

30 Figure 2 is a top view of the invention with certain parts broken away.

Referring again to Figure 1 the reference character 1 indicates generally a suction cleaner comprising the usual motor casing 2, fan chamber 3 and main nozzle casing 4. Front supporting wheels 5, of which only one is shown, carry the weight of the front end of the machine and are fixedly journaled by bearing members 6 within the wheel-pockets 7 of the main nozzle casting 40 formed by the walls 8 and 9. The pockets 7 are divided from the nozzle in which the flow of air takes place by the walls 9.

Supported and pivoted at 12 upon an arm 10 extending rearwardly at the sides of the nozzle 45 casing are the side members 11 of the floating sub-nozzle type hereinafter described. The members 11 extend forward through the pockets 7, making intimate contact with the forward wall 9 thereof, into the main nozzle chamber 13. Referring to Figure 1 reference character 14 indicates a slot in the member 11 which is adapted to enclose the bearing member 6 of the wheel 5. An arcuate rack 15 is formed on the member 11 on a curvature which has as its center the pivot 55 member 12. The forward end of the member 11

is provided with a slot 16 adapted to receive and seat a supporting shaft 17 of the rotor 18. In the operative position the rotor 18 is carried between the members 11, 11 and moves with them. Means 19 shown pivoted at the forward end of 60 the member 11 is a spring pressed retaining member for the shaft 17 and in itself forms no part of the present invention.

Referring again to Figs. 1 and 2 a forward connecting member 20 forming the forward 65 nozzle-lip connects the two side members 11, 11 and has fastened to its upper edge a strip of chamois or other flexible material 21 which overlies the upper edge of the member and extends beside the outer edge and is adapted to make 70 sliding contact with the inner edge of the main nozzle casing and prevent air leakage therebetween.

Spaced rearwardly from the connecting member 20 is a second connecting member 22 forming 75 the rear nozzle-lip which also extends between the two side members 11, 11 and bends back upon itself across its entire length and tightly clamps the edge of a strip of flexible air-tight material 23 which is secured at its other side in any ordinary manner to the bottom plate 24 of the nozzle. The member 22 is provided at each end with lugs 35 which are clamped to the members 11, 11 by screws 36 permitting the separation of the lip and the members 11, 11 if desired.

85 The members 20 and 22 forming the front and rear lips together with the members 11, 11 included therebetween, as the sides, form a sub-nozzle which is floating with respect to the main nozzle and the machine proper and which is actuated and adjusted as hereinafter described.

Seated directly above the main nozzle and having its lower side 26 substantially co-extensive with the upper face thereof is a bellows indicated generally by the reference character 25. The upper face 27 of the bellows is hingedly connected to the side 26 and a spring 28 located at the pivot point tends to keep the bellows in the extended position. Openings 29 connect the interior of the bellows with the interior of the nozzle and insure 100 that the same pressure will at all times exist in those members.

Pivotedly connected to each end of the upper face 27 of the bellows by a pin 31 is an arm 30 which extends downwardly and makes pivotal 105 contact with the lever arm 32 which is fixedly connected at its other end to the transverse rotatable shaft 33 upon each end of which is mounted a segmental pinion 34 in intermeshing 110 relation with an arcuate rack 15 formed on the

side of a member 11. The segmental pinions 34 on each side of the nozzle are non-rotatably mounted on the shaft 33 thereby prohibiting relative movement between the two sides of the floating nozzle.

In the operation of the suction cleaner it is desirable at all times to have the nozzle lips make sufficient contact with the surface covering undergoing cleaning to insure a sufficient vacuum 10 to lift the covering from the surface proper. Such lifting permits the effective beating and sweeping of the lifted part of the covering and further causes the inrushing air to pass through the pile of the covering and remove the dirt 15 lodged therein in gaining entrance to the nozzle instead of over the pile as is the case where the nozzle lips are spaced at too great a distance from the covering. It is further desirable that too great a vacuum be not attained for such a condition 20 results in a decrease in the cleaning power through retardation of the rotor speed caused by the pressure of the lifted covering thereagainst and also in an increase of the resistance of the machine to movement through an inordinate displacement of the covering within the nozzle and the resultant pressure against the lips thereof.

A cleaner constructed in accordance with the present invention insures the aforementioned desirable characteristics through its operation 30 which is as follows: The cleaner is placed on the surface covering to be cleaned and the motor started. As the motor starts the nozzle lips are found tightly pressed to the surface covering by the action of the spring 28 in extending the bellows 35 thereby lifting the arm 30 which causes the shaft 33 to rotate with the resultant angular motion of the sub-nozzle about the pivot points 12 as the segmental pinion 34, through its rotation with the shaft 33, forces the toothed surface 15 downward. The tight sealing of the nozzle lips to the covering prevents a large inrush of air and as the air in the nozzle is exhausted by the cleaner fan a vacuum is formed therein. As the bellows are directly connected to the nozzle by the 40 passageways 29 the same pressure exists in the bellows as is found in the nozzle. The spring 28 is designed to resist a certain force and upon the vacuum in the bellows attaining a certain value below atmospheric pressure the exterior 45 atmospheric pressure on the bellows overcomes the spring-force and the bellows begin to collapse. This results in an upward movement of the nozzle lips through the aforescribed linkage with a consequent greater inrush of air between the nozzle lips and the surface covering. Upon the vacuum in the nozzle and bellows being 50 decreased by this incoming air to a value where the collapsing pressure on the bellows is equalled by the resisting force of the spring 28 a state of equilibrium is reached and no further adjustment takes place until a variation from this state of equilibrium occurs. Such a variation would be caused by an increase in the amount 55 of inrushing air caused by a decrease in the height of the pile. In such a case the spring-force would instantly become greater than the collapsing pressure on the bellows, the bellows would be extended with a consequent lowering of 60 the nozzle lips which would decrease the volume of the inrushing air thereby raising the vacuum until equilibrium was again reached.

The invention, as described, combines in a simple, rugged and novel structure the sensitivity 75 required in the automatically adjusted nozzle

which is requisite for constant efficiency in a suction cleaner.

It is further clear that in the event that it is desired to remove the rotor for any reason that the operation is exceedingly simple. The pin 31 80 is removed permitting unlimited rotation of the shaft 33 and the segmental pinion 34. The screws 35 are removed thereby releasing the rear lip 22 and the sub-nozzle may then be rotated about the points 12, 12 until it reaches a position approximately ninety degrees displaced from its working position. This rotation is possible with the pin 31 removed for then the segmental pinion 34 can rotate until out of mesh with the rack 15. The wheel-supporting shaft 6 85 passes out through the slot 14 provided for that purpose. With the rotor in the lowered position it is readily removed from the sub-nozzle frame.

I claim:

1. In combination in a suction cleaner, a main nozzle, a floating sub-nozzle, and air pressure-responsive automatic height-adjusting means controlling the position of said sub-nozzle, said means comprising a bellows open to said nozzle and adapted to be collapsed and expanded by 95 nozzle-pressure variation and connecting linkage between a movable part of said bellows and said sub-nozzle adapted to raise and lower said sub-nozzle as said bellows is collapsed and expanded.

2. In combination in a suction cleaner, a main 105 nozzle, a floating sub-nozzle within said main nozzle, a bellows open to said nozzle and adapted to be expanded and contracted with variation of nozzle pressure, and means connecting said bellows to said sub-nozzle to move said sub-nozzle 110 upon operation of said bellows.

3. In combination in a suction cleaner, a main nozzle fixedly positioned above the surface being cleaned, a floating sub-nozzle within the main nozzle pivotally connected thereto and having surface-contacting lips movably connected to said main nozzle in air-tight relation, and automatic air pressure-responsive height-adjusting means 115 operatively connected to said sub-nozzle.

4. In combination in a suction cleaner, a main 120 nozzle, a floating sub-nozzle within the main nozzle in sealed relation thereto, sealing means comprising a front lip on the sub-nozzle carrying and compressing a strip of air-tight material 125 against the main nozzle and a rear lip on said sub-nozzle flexibly connected to said main nozzle in sealed relation thereto, and air pressure-responsive height-adjusting means for said sub-nozzle.

5. A suction cleaner comprising a main nozzle, 130 a floating sub-nozzle within said main nozzle in sealed relation thereto, said sub-nozzle comprising side plates pivoted to said main nozzle and transverse lips adapted to contact a surface covering undergoing cleaning, an agitator carried by 135 said sub-nozzle, pressure-responsive means responsive to nozzle-pressure variations, means interiorly connecting said means to said nozzle, and means operatively connecting said first-mentioned means to said sub-nozzle to adjust said sub-nozzle relative to the nozzle upon pressure variations therein.

6. A suction cleaner having a main nozzle, a floating sub-nozzle within said main nozzle in 145 sealed relation thereto, said sub-nozzle having a side plate pivoted to said main nozzle casing, a toothed rack on said side plate, transverse lip members connected to said side plate, a rotatable pinion on said main nozzle intermeshing with 150

- 1 said rack, and nozzle pressure-responsive means
2 operatively connected to said pinion.

3 7. A suction cleaner comprising a main nozzle,
4 a floating sub-nozzle within said main nozzle,
5 automatic means for controlling the position of
6 said sub-nozzle in said main nozzle, said means
7 comprising an air pressure-responsive bellows
8 open to said nozzle and adapted to be collapsed or
9 expanded upon nozzle-pressure variation, a
10 member pivotally connected to a movable part of
11 said bellows, a lever arm pivotally connected to
12 said member at one of its ends and fixedly at-
13 tached to a rotatable pinion gear at its other end,
14 and a toothed section on said sub-nozzle adapted
15 to coact with said pinion gear.

16 8. A suction cleaner comprising a main nozzle,
17 a fluid pressure-responsive bellows mounted
18 thereon and interiorly connected therewith and
19 a floating nozzle within said main nozzle, and
20 power transmission means connecting said float-
21 ing nozzle and said bellows to move said floating
22 nozzle relative to said main nozzle upon the
23 movement of said bellows.

24 9. A suction cleaner comprising a main noz-
25 zle having an opening in its upper surface, a fluid
26 pressure-responsive bellows mounted thereon,
27 said bellows comprising a lower plate having an
28 opening therein connecting with said main nozzle
29 opening, an upper plate hinged to said lower
30 plate, a spring at the hinge exerting a separating
31 force and flexible air-proof side material connect-
32 ing said plates, a floating frame within said main
33 nozzle, nozzle lips carried by said frame and pow-
34 er transmission means connecting said bellows to
35 said frame to move said frame relative to said
36 nozzle upon expansion or contraction of said bel-
37 lows.

38 10. In a suction cleaner, a nozzle, a floating
39 sub-nozzle in operative relation to said main
40 nozzle, a pressure-responsive device operatively
41 connected to said nozzle, and means connecting
42 said pressure-responsive device to said sub-nozzle
43 to adjust said sub-nozzle relatively to the nozzle
44 upon pressure variations therein.

45 11. In a suction cleaner, a nozzle, a surface-
46 contacting lip movably supported relative to said
47 nozzle, a pressure-responsive device, means in-
48 teriorly connecting said device to said nozzle, and
49 second means connecting said lip and said device

50 and adapted to vertically adjust said lip relative
51 to the nozzle upon pressure variations therein.

52 12. In a suction cleaner, a body, suction-creat-
53 ing means, means for supporting said body above
54 a surface covering undergoing cleaning, a surface-
55 contacting member transportable relative to said
56 body and to a surface covering undergoing clean-
57 ing, fluid-pressure-responsive means operatively
58 connected to a point on the low pressure side of
59 said suction-creating means, and means con-
60 nnecting a moving part of said pressure-responsive
61 means to said member to transport said member
62 relative to said body and to the surface covering
63 undergoing cleaning upon variations in suction.

64 13. The construction set forth in the preced-
65 ing claim characterized by the fact that said
66 member comprises a rotary agitator.

67 14. In a suction cleaner a body, means for sup-
68 porting said body above a surface covering under-
69 going cleaning, an air passageway, a surface-
70 contacting lip defining a side of said passageway,
71 said lip being movably mounted relative to said
72 body, a fluid pressure-responsive device exposed
73 to the pressure existing in said passageway, and
74 means connecting a moving part of said device
75 to said lip to move said lip upon pressure varia-
76 tions.

77 15. In a suction cleaner, a body, means for sup-
78 porting said body above a surface covering under-
79 going cleaning, an air passageway, spaced surface-
80 contacting lips defining the mouth of said pas-
81 sageway and mounted for vertical movement rela-
82 tive to said body, a fluid-pressure-responsive de-
83 vice connected to said passageway, and means
84 connecting a moving part of said device to said
85 lips to move said lips upon pressure variations.

86 16. In a suction cleaner, a body, means for sup-
87 porting said body above a surface covering under-
88 going cleaning, and air passageway, spaced sur-
89 face-contacting lips defining the mouth of said
90 passageway and mounted for vertical movement
91 relative to said body, a surface covering agitator
92 mounted for movement with said lips, a fluid-
93 pressure-responsive device connected to said pas-
94 sageway, and means connecting a moving part of
95 said device to said lips to move said lips and
96 agitator upon pressure variations.
